UNITED STATES PATENT OFFICE.

MELVIN JINCKS AND CLARENCE W. STANTON, OF COHOCTON, NEW YORK.

SAWBUCK.

SPECIFICATION forming part of Letters Patent No. 691,633, dated January 21, 1902.

Application filed October 31, 1901. Serial No. 80,709. (No model.)

To all whom it may concern:

Be it known that we, MELVIN JINCKS and CLARENCE W. STANTON, citizens of the United States, residing at Cohocton, in the county of 5 Steuben and State of New York, have invented a new and useful Sawbuck, of which the following is a specification.

This invention relates to sawbucks, and has for its object to provide for conveniently and 10 effectively holding the material to be cut snugly upon the buck without requiring the operator to place his knee upon the log.

It is furthermore designed to arrange the log-holding means so that it may be conveniently applied to and removed from the log 15 and also manipulated by one of the feet of the operator to draw said means into snug engagement with the log.

Another object is to arrange for folding the 20 log-holding means, so as to reduce the size of the device when not in use.

With these and other objects in view the present invention consists in the combination and arrangement of parts, as will be herein- 25 after more fully described, shown in the accompanying drawings, and particularly pointed out in the appended claims, it being understood that changes in the form, proportion, size, and minor details may be made 30 within the scope of the claims without departing from the spirit or sacrificing any of the advantages of the invention.

In the drawings, Figure 1 is a perspective view of a sawbuck having the present form 35 of log-holding means applied thereto. Fig. 2 is a longitudinal sectional view thereof. Fig. 3 is a detail sectional view taken through the sawbuck to show the connection between the opposite crossed standards thereof.

40 Like characters of reference designate corresponding parts in all the figures of the drawings.

In carrying out the present invention it is preferred to provide the sawbuck with at 45 least three pairs of crossed leg-standards 1, 2, and 3, respectively, the adjacent pairs of which are connected by the respective cross-bars 4, the tops and bottoms of which are recessed or grooved for the reception of the upper and lower tie rods or bars 5, the heads 50 of which are let in flush with the outer side of one of the end pairs of leg-standards, the

opposite ends of the rods or bars being provided with nuts 7, whereby the parts of the sawbuck are firmly connected, and any looseness therein may be conveniently taken up. 55 The intermediate pair of leg-standards and one of the end pairs rise from a pair of parallel sills 8, which project a suitable distance at one side of the sawbuck and are designed 60 to rest upon the ground. The outer ends of the sills are provided with upstanding posts or uprights 9, between which a treadle is hung, said treadle comprising inner and outer sections 10 and 11, respectively, which are connected by means of a hinge-joint 12. The rear end of the main section 10 is situated between the posts 9 and is provided with a pair of bearing-eyes 13, which pivotally embrace a rod or cross-bar 14, carried by the upper ends 70 of the posts 9. Beneath the treadle-section 10 there is placed a helical spring 15, which bears in opposite directions against the under side of the treadle, and a plate or platform 16, supported upon the sills, whereby 75 the treadle is yieldably supported and is normally held in an elevated position. The outer end of the outer treadle-section 11 is provided upon its under side with an antifriction-roller 17, which is designed to travel upon 80 a supporting-plate 18, which has its inner end projected between the sills 8 and pivotally connected to a cross-bar 19 in any suitable manner.

As best illustrated in Fig. 2, it will be seen 85 that the hinged joint of the treadle is located below and adjacent to the cross-bar of the sawbuck and works between the intermediate pair of standards and the adjacent outer pair of standards. Moreover, the outer section 90 of the treadle and the supporting-plate 18 may be folded upwardly and inwardly into the space between the adjacent end standards and the intermediate standards, as shown in dotted lines, thereby to reduce the size of the 95 device when not in use, the plate 18 fitting snugly between the pairs of leg-standards, so as to frictionally engage the same and thereby be held in its folded position. In addition to this folding feature the joint 12 permits of the outer treadle-section being 100 inclined downwardly, so as to be in position for conveniently placing the foot thereon, instead of being inclined upwardly at a consid-

erable elevation, as would be the case if the treadle were in a single piece.

The outer end portion of the rear treadle-section is provided with a staple or eye 20, to which is loosely connected the lower end of the upstanding shank portion 21 of a hook 22, said hook being of a length to engage over the top of the cross-bar 4 of the sawbuck, so as to hook over a log, as indicated in Fig. 1 of the drawings. A long staple 23 is driven into the back of the cross-bar 4 and receives the shank of the hook, so as to form a slotted guide therefor, against the outer end of which the shank rests, as shown in Fig. 2, so as to support the hook at its outer limit when not in use for holding a log in the crotches of the sawbuck. As the hook would not effectually hold a bundle of small sticks in the crotch of the sawbuck, I have provided means especially designed for this purpose, as best illustrated in Fig. 2 of the drawings, and comprising a chain 24, which has one end connected to the staple or eye 20, with its free end portion adapted for adjustable engagement with a swinging hook 25, connected to the inner end portion of the treadle-section 11, whereby the intermediate portion of the chain may be passed over the bundle of sticks, so as to embrace the same and prevent lateral displacement thereof.

In using the present log-holding means the hook or the chain is engaged over the log or bundle of sticks, and then the operator places one foot upon the treadle - section 11 and presses downwardly thereon, thereby to draw the hook or chain into snug engagement with the log or bundle of sticks and hold the latter snugly within the crotch of the sawbuck, whereby it is not necessary for the operator to place one of his knees upon the log. After a portion has been cut off from the log the operator removes his foot from the treadle, so that the latter may be elevated by the spring 15, thereby to loosen the hook or chain, so that the log may be moved in an endwise direction to project the log for another cutting.

Although two pairs of standards are sufficient to form a sawbuck, yet it is desirable to have one or more additional pairs of leg-standards, so as to increase the length of the sawbuck, as the pairs of standards 1 and 2 are rather close to each other.

The arrangement of the log-holding means as illustrated in the accompanying drawings is for a right-handed operator, and it will of course be understood that said means would be applied to the other end of the buck for the use of a left-handed operator.

60 What we claim is—

1. The combination with a sawbuck, of a spring-treadle formed in pivotally-connected sections, one of the latter having a fixed terminal pivotal support, the outer free end of the other treadle-section being normally inclined downwardly and free to slide, and log-holding means carried by the treadle.

2. The combination with a sawbuck, having a rear extension, of an intermediately-jointed spring-supported treadle having one end pivotally connected to the extension and its opposite end inclined downwardly and free to slide during the swinging movement of the treadle, and log-holding means carried by the treadle. 70

3. The combination with a sawbuck, of supporting-sills therefor projected in rear thereof, a spring-supported treadle having an intermediate pivotal joint and pivotally supported at its rear end upon the sills, the front end of the treadle being free to slide under the swinging movement of the treadle, and log-holding means carried by the treadle. 75

4. The combination with a sawbuck, of supporting-sills therefor projected in rear thereof, a pair of posts rising from the rear end of the sills, a platform in front of the posts, a treadle comprising front and rear sections which are pivotally connected, the outer end of the rear section being pivotally connected 85 between the posts, and the outer end of the front section being free to slide during the swinging movement of the treadle, an elevating-spring interposed between the platform and the rear treadle-section, and log-holding 90 means carried by the treadle.

5. The combination with a sawbuck, of a flexibly-jointed treadle, a pivotal support for one end of the treadle, an antifriction-roller carried by the opposite free end of the treadle, 100 a plate carried by the buck and disposed for the support of the antifriction-roller, and log-holding means carried by the treadle.

6. The combination with a sawbuck, of a flexibly-jointed treadle, a pivotal support for 105 one end of the treadle, an antifriction-roller carried by the opposite free end of the treadle, a vertically-swinging plate pivotally connected with the sawbuck and disposed beneath the free end of the treadle in normal supporting engagement with the antifriction-roller, and log-holding means carried by the treadle. 110

7. The combination with a sawbuck having a lateral extension, of a treadle pivoted thereto and comprising pivotally-connected sections projected between the leg-standards of the buck, the outer treadle-section being capable of being folded upwardly between said leg-standards, and also provided at its outer end with an antifriction supporting - roller, 115 and a plate pivoted between the leg-standards and adapted to rest upon the ground for the support of the roller, said plate also being capable of being folded upwardly and inwardly between the leg-standards, and log-holding 120 means carried by the treadle.

8. The combination with a sawbuck, of supporting-sills therefor projected at one side of the buck, posts rising from the rear end of the sills, a treadle lying between and projected at opposite sides of the leg-standards of the buck, the treadle being provided with an intermediate hinged joint, the rear end of the treadle being pivotally supported between 130

- the posts, a spring interposed between the sills and the rear portion of the treadle, an antifriction-roller carried by the under side of the outer portion of the treadle, a plate pivoted between the standards and adapted to rest upon the ground for the support of the antifriction-roller, and log-holding means carried by the rear portion of the treadle.
9. A sawbuck, comprising opposite pairs of crossed leg-standards, a cross-bar extending between the pairs of standards at the points of crossing thereof, the top and bottom edges
- of the cross-bar being provided with grooves, and tie-bolts piercing the opposite pairs of leg-standards and lying in the respective grooves.
- In testimony that we claim the foregoing as our own we have hereto affixed our signatures in the presence of two witnesses.
